C. P. SIBLEY,
FASTENER FOR PAPERS AND OTHER MATERIALS,
APPLICATION FILED NOV. 10, 1920.

1,397,787.

Patented Nov. 22, 1921.

UNITED STATES PATENT OFFICE.

CEDRIC PUTNAM SIBLEY, OF DETROIT, MICHIGAN.

FASTENER FOR PAPERS AND OTHER MATERIALS.

1,397,787.

Specification of Letters Patent.

Patented Nov. 22, 1921.

Application filed November 10, 1920. Serial No. 423,143.

To all whom it may concern:

Be it known that I, CEDRIC PUTNAM SIBLEY, a citizen of the United States, residing at Detroit, in the county of Wayne 5 and State of Michigan, have invented a certain new and useful Improvement in Fasteners for Papers and other Materials, of which the following is a full, clear, and exact description.

- 10 This invention relates to a paper fastener of the self-piercing type represented in the well-known "Challenge" eyelet, which is manufactured under the patent to Edward L. Sibley, No. 358,225, dated February 22, 1887. It is desirable, in some cases, to mechanically feed and set such fasteners, but those, like the "Challenge", which have a tubular barrel do not readily conform to feeding mechanism.
- 20 It is the object of the present invention to provide a self-piercing fastener which lends itself readily to use on or in connection with a feeding mechanism, without sacrificing any of the advantages of this 25 type of fastener and still retaining its facility of removal.

The invention consists of a fastener, for use in connecting a plurality of sheets of paper or other material, having a substantially rectangular barrel portion which may be and is here shown as adapted to be driven through the material to be fastened, and also having terminal flanges at its end opposite its driven end; these flanges being capable 35 of being reverted in order to remove a set fastener when desired; the construction being such that the individual fasteners or series of such fasteners connected in a strip, may be placed in a clip or holder or race- 40 way or magazine of a setting machine and fed by gravity or otherwise to the setting tools; and in case of the strip form of fasteners, means may be provided for severing the successive fasteners as they are presented for setting; and as an alternative the fasteners may be formed in the act of setting, as I will proceed now to explain and finally claim.

In the accompanying drawings illustrating the invention, in the several figures of which like parts are similarly designated, Figure 1 is a perspective view of one form of fastener. Fig. 2 is a plan view of a portion of a blank, from which such fastener 55 may be made. Fig. 3 is a perspective view of a strip of connected fasteners. Fig. 4 is

a sectional elevation illustrating the first operation in setting the fastener on pieces of paper or other material. Fig. 5 is a similar view showing the second operation, 60 and Fig. 6 represents the final setting operation. Fig. 7 is a perspective view of another form of fastener; Fig. 8 is a plan view of a portion of a blank from which it may be made; Fig. 9 is a perspective view of a strip 65 of such fasteners; and Figs. 10, 11 and 12 are elevations representing the three steps of setting the fastener. Figs. 13, 14 and 15 are diagrammatic elevations illustrating another form of the invention in which the 70 fastener is formed *in situ* from a flat strip of metal and set in a series of successive operations.

Referring to that form of the invention illustrated in Figs. 1 to 6 inclusive, the fastener has the substantially rectangular barrel 1, the sides of which are substantially parallel, with the closed end 2, the open end 3 and the lateral flanges 4 on opposite sides of said open end. This fastener may be 80 made in a variety of ways, either singly or in strips. For example, the flat strip 5, Fig. 2, may be cut crosswise from both sides nearly to the center, as represented by the lines 6 and 7, so as to leave an unsevered 85 portion 8 which serves to hold the fasteners in strip form, and then said strip is die-pressed or otherwise formed into a substantially inverted U-shape, as represented in Fig. 3. 90

When thus manufactured, the fasteners are adapted for use in a machine having an automatic or other feed, such as clips, raceways or magazines, by which the fasteners are successively fed one by one to the setting 95 mechanism and severed as individually delivered.

As shown in Figs. 4, 5 and 6, fasteners of the character described are adapted to be driven through the material to be fastened, 100 without previous perforation of the material, the barrel 1 being driven through the material in the direction of its closed end 2 until the flanges 4 abut against the back of the material, and then, by means of suitable 105 setting dies or tools, this barrel is collapsed, as indicated in Fig. 5, and finally flattened down or extended out laterally, substantially parallel with the flanges and with the face of the material to be fastened, as indicated in 110 Fig. 6.

Instead of manufacturing the fastener

as just described, it may be made from a narrow strip 9, as shown in Figs. 7, 8 and 9, equal in width to the width of the finished article, and preferably partly severed by laterally formed notches 10 on opposite sides of the strip, and then the strip between such notches is bent up to form the parallel-sided barrel 11, Fig. 9. The other elements of this fastener are in general the same as previously described and are so designated. This construction also lends itself readily to a feeding mechanism in a setting machine, where provision is made for driving the barrel through the material to be fastened, as indicated in Fig. 10, and then collapsing it, as indicated in Fig. 11, and finally flattening it down, as in Fig. 12, the strip being severed on the lines of the notches as each individual fastener is driven through the material to be fastened.

As a further illustration of my invention, reference is made to the construction shown in Figs. 13, 14 and 15, wherein a flat strip of metal 12, unsevered, or partly severed as in Fig. 8, is wound on a spool 13 and fed thence to suitable forming tools, comprising a pin 14 and a die 15, with the material 16 to be fastened superposed upon the strip. Upon the descent of the die, the strip of metal is drawn from the spool over the pin and forced through the material to be fastened, as shown in Fig. 14, and a fastener length severed by means of the supplemental shearing blades 17, and thereupon, upon further movement of the die, the rectangular formation of the fastener is completed, as shown in Fig. 15; after which the barrel may be collapsed, as indicated in either Figs. 4 to 6 or 10 to 12.

In any case, the fastener may be removed from the fastened material by reverting the flanges, as indicated by dotted lines in Fig. 6, and pulling it out in the direction of arrow 18, Fig. 6, without marring the material.

I have thus described a number of different ways of carrying out the principle of the invention, but wish it to be understood that I realize that the invention is susceptible of further variations within the scope of the claims following.

In all of the forms of the fastener herein explained, it is composed of a closed or leading end, parallel sides and terminal flanges on said sides, the fastener being open on the

other sides and the bottom. Thus the fasteners may be made from flat strips of metal without waste or scrap. Furthermore, these characteristics peculiarly adapt the fastener to automatic setting machines since whether in strip or individual form the two sides serve as guides for the fasteners when in the clip or raceway, and the open sides adjust them to the setting tools.

While for convenience I have referred to my invention as a paper fastener, it is to be understood, also, that the fastener may be used for fastening material other than paper, and consequently the claims will be understood as not limited to the use of the invention for fastening sheets of paper.

What I claim is:—

1. A paper fastener, composed of a strip of metal bent transversely into substantially rectangular form, and having a closed leading end and an open end, said closed end adapted to be passed through the material to be fastened, and a pair of parallel sides terminating in laterally extended flanges next to the open end, the other sides being open.

2. A paper fastener, made from a flat narrow strip of metal bent in the middle transversely, thereby forming substantially parallel and flat sides which constitute the self-piercing element of the fastener, the edges of said sides being in alinement and parallel, and the ends thereof bent outwardly to form the flange or base of the fastener, the other sides and the end next to the flange being open.

3. A paper fastener, in strip form, having a closed end barrel adapted to be driven through the material to be fastened, and bottom flanges, severed from the strip in the act of setting.

4. Paper fasteners of substantially inverted U-shape arranged in strip form to facilitate their use in a fastener setting machine, the strip being partially severed transversely to individualize the fasteners and provide for their separation from the strip one by one.

In testimony whereof I have hereunto set my hand this eighth day of November, 1920.

CEDRIC PUTNAM SIBLEY.

Witnesses.
